[57] CLAIM

The ornamental design for a set of grips for a roller frame handle, as shown and described.

DESCRIPTION

FIG. 1 is a perspective view of a set of grips for a roller frame handle showing my new design, with the broken line showing of a roller frame handle being for illustrative purposes only and forming no part of the claimed design; FIG. 2 is a right end elevational view thereof; FIG. 3 is a left end elevational view thereof; FIG. 4 is a top plan view thereof, the bottom plan view being a mirror image of the top view shown; and, FIG. 5 is a front elevational view thereof, the rear elevational view being a mirror image of the front elevational view shown.
